UNITED STATES PATENT OFFICE.

GEORGE W. ROBERTS, OF RAVENNA, NEBRASKA;

CEMENT BUILDING-BLOCK.

No. 322,078.

Specification of Letters Patent.

Patented May 29, 1906.

Application filed May 10, 1905. Serial No. 259,798.

To all whom it may concern:

Be it known that I, GEORGE W. ROBERTS,
a citizen of the United States, residing at Ravenna,
in the county of Buffalo and State of Nebraska,
have invented new and useful Improvements in Cement Building-Blocks, of
which the following is a specification.

This invention relates to an improvement in building-blocks constructed and arranged to provide when assembled a bonded wall.

The main object of the invention is the production of a block of hollow formation and so constructed as to adapt it to interlock with the next adjacent blocks, whereby to provide a bonded wall having uninterrupted vertical air-spaces.

A further object of the invention is to so construct the building-block that the interlocking thereof with the contiguous blocks will provide an air-space intermediate the ends of the block.

The preferred form of the invention is illustrated in the accompanying drawings and will be described in detail in the following specification and the novel features thereof pointed out in the claims.

In the drawings, Figure 1 is a perspective view illustrating a section of a wall constructed of my improved block. Fig. 2 is a vertical central section through the wall constructed of my improved block: Fig. 3 is a plan of what I term the "wall-block." Fig. 4 is a plan of a single corner-block. Fig. 5 is a plan of a return corner-block.

35 Referring particularly to Figs. 1, 2, and 3 of the drawings, wherein is clearly illustrated my improved block constructed and arranged for ordinary wall-building purposes, it will be noted that the block comprises, preferably, 40 a rectangular body 1, which may be formed or molded from any suitable or desired material. The block is formed with a vertically-extending centrally-arranged opening 2 to provide the usual dead-air space transverse 45 of the block.

The block is arranged for bonding with the adjacent blocks by forming one end of the block with a vertically-arranged wedge-shaped tongue 3 and the opposite end with a wedge-shaped groove 4. The transverse dimension of the tongue is approximately equal to the interior transverse dimension of the groove 4, so that when the blocks are assembled in bonding relation the tongue of one block will closely fit within the mouth of the groove of the next adjacent block, the inclina-

tion of the edges of the tongue and of the walls of the groove providing for a close sliding fit, as will be evident.

It is highly desirable, however, to provide 60 a dead-air space intermediate the adjacent blocks, and to arrange this I form the tongue of less length than the teeth of the groove, whereby when said tongue is inserted so that the terminals of the walls of the groove, as 5, 65 abut against the edges of the block adjacent the base of the tongue, as at 6, an air-space 7 is formed intermediate the end of the tongue and the base of the groove.

In providing a corner-block for use in a wall constructed of my improved blocks I have found it desirable to provide the block therefor, as 8, with one plain end 9 and the opposite formed with a groove 10, similar to the groove 4, or with a tongue similar to the tongue 3, as may be required for the proper assembling of the corner-block in a series. 75

To provide for a corner-block which bonds the meeting ends of a course of blocks arranged at right angles, as in building side and end walls, I provide what I term a "return" corner-block 11, comprising practically duplicates of the wall-blocks 1, formed as an integral block with the side edge of one connected to the end of the other, thus providing a right-angle block provided with two vertically-arranged apertures or openings 12, the terminals of the block having the hereinbefore-described tongue 13 and groove 14. It is to be understood, of course, that the return corner-block may be constructed as desired for the particular work in hand, the respective block-sections being arranged at a right angle to each other or at any angle desired.

It is to be understood, of course, that the blocks are to be arranged in the usual staggered order—that is, the air-space 2 of one block is arranged out of alignment with the air-space of the block in the course next below or above. By providing the air-space 7 intermediate the adjacent ends of the connected blocks I arrange a continuous air-space vertical of the wall, as said air-spaces 7 in one course of block will align with the air-spaces 2 of the blocks in the course immediately below and above. 95 100 105

It will be noted that a wall constructed of my improved block is bonded throughout, as the respective blocks are locked to each other in order to prevent independent movement and yet at the same time provide air-space intermediate the ends of adjacent blocks.

The blocks may be constructed of any suitable material and may be pressed or molded, though I prefer the ordinary cement construction.

5 Having now described my invention, what I claim as new, and desire to secure by Letters Patent, is—

1. A building-block comprising a body formed with a central vertically-arranged opening, one end of the body being formed with a dovetailed groove extending vertically thereof and of greater width at its inner end than the width of said opening, the opposite end of the body being provided with a wedge-shaped rib of less length than the depth of the groove, the dovetailed groove and rib being of greater extent transverse the block than than the similar dimension of the vertically-arranged opening, whereby to provide the maximum air-space at the ends of the block.

2. A building-block comprising a body including two integral sections arranged at a right angle to each other, and each of the sections being formed with centrally-arranged openings, the terminal of one section having 25 a wedge-shaped groove, and the terminal of the other section being formed with a wedge-shaped rib of less length than the depth of the groove, the dovetailed groove and rib being of greater extent transverse the block than 30 the similar dimension of the vertically-arranged opening, whereby to provide the maximum air-space at the ends of the block.

In testimony whereof I affix my signature in presence of two witnesses.

GEORGE W. ROBERTS.

Witnesses:

W. F. RICHARDSON,
W. G. BIDGOOD.
